To all whom it may concern:

Be it known that I, Roy S. Sanford, a citizen of the United States, residing at Oakville, in the county of Litchfield and State of Connecticut, have invented a new, original, and ornamental Design for a Grab Bar or Similar Article, of which the following is a specification, reference being had to the accompanying drawing, forming a part thereof.

The characterizing feature of the grab bar or similar article resides in the provision of a pair of brackets of substantially the configuration shown disposed in horizontally and vertically offset relation to each other in a common plane and a substantially U-shaped bar substantially rectangular in cross section secured to and between the brackets in a plane at substantially a right angle to said common plane and oblique to the major dimension of each bracket.

I claim:
